(57) **CLAIM**

The ornamental design for a buttstock, as shown and described.

DESCRIPTION

The invention described and claimed herein may be manufactured, used, and licensed by or for the U.S. Government for U.S. Government purposes.

FIG. 1 is a perspective view showing our new design as mounted on a rifle;

FIG. 2 is a side view thereof, the opposite side being a mirror image;

FIG. 3 is a top view thereof, the bottom view being a mirror image; and,

FIG. 4 is an end view thereof.

The rifle in FIG. 1 is shown in broken lines for illustrative purposes only and forms no part of the claimed design.

1 Claim, 4 Drawing Sheets
